UNITED STATES PATENT OFFICE.

SAMUEL M. RIKER, OF CHESTER, NEW JERSEY.

BELT BUCKLE.

1,406,281.

Specification of Letters Patent. Patented Feb. 14, 1922.

Application filed May 6, 1921. Serial No. 467,365.

To all whom it may concern:

Be it known that I, SAMUEL M. RIKER, a citizen of the United States, residing at Chester, in the county of Morris and State 5 of New Jersey, have invented certain new and useful Improvements in Belt Buckles; and I do hereby declare the following to be a full, clear, and exact description of the invention, such as will enable others skilled 10 in the art to which it appertains to make and use the same, reference being had to the accompanying drawings, and to characters of reference marked thereon, which form a part of this specification.

15 This invention relates, generally, to improvements in buckles; and, the present invention has reference, more particularly, to a novel construction of belt-buckle comprising in combination with the ornamental 20 main face-plate or body of the buckle, a pair of clamping members adapted to be brought into active engagement with each other, both members co-operating with each other to bring the belt-body into a firmly 25 clamped relation with the back of the said main face-plate or body of the buckle.

The present invention has for its principal objects to provide a novel and simply-constructed belt-buckle comprising a pair 30 of pivoted clamping elements adapted to engage each other during the clamping operation with the belt-body, the two clamping elements or members co-operating with each other to provide a more secure and positive 35 clamping action against the belt-body, the arrangement and construction of the two co-operating clamping elements or members being such, so that the clamp-means will readily accommodate itself in 40 operation to various thicknesses of belt-bodies with which the buckle may be employed, without unduly straining the parts of the buckle, while providing a doubly locked and adequate gripping or clamping 45 effect when in use.

Other objects of the present invention not at this time more particularly enumerated will be clearly understood from the following detailed description of the present invention.

With the various objects of the present invention in view, the said invention con-

sists, primarily, in the novel belt-buckle hereinafter set forth; and, the said invention consists, furthermore, in the novel arrangements and combinations of the various devices and parts, as well as in the details of the construction of the said parts, all of which will be more fully described in the following specification, and then finally embodied in the clauses of the claims which are appended to and which form an essential part of the said specification.

The invention is clearly illustrated in the accompanying drawings, in which:

Figure 1 is a front face view of a belt-buckle showing one embodiment of the principles of the present invention, operatively associated with a belt-body.

Figure 2 is a rear face view of the buckle, and portions of the belt-body to which it is attached; and Figure 3 is a side edge elevation of the same.

Figure 4 is a central longitudinal vertical section, on an enlarged scale, of the belt-buckle, and portions of the belt-body to which it is attached; and Figure 5 is a transverse vertical section of the same, said section being taken on line 5—5 in said Figure 4, looking in the direction of the arrow α .

Figure 6 is a rear face view of a belt-buckle of a slightly modified form of construction, but still embodying the principles of the present invention; and Figure 7 is a longitudinal vertical section of the same.

Similar characters of reference are employed in all of the said above described views, to indicate corresponding parts.

Referring now to the several figures of the drawings, the reference-character 1 indicates the complete belt-buckle, the same comprising a main member or buckle-body consisting of a face-plate 2, which is preferably outwardly convexed, and is provided along its longitudinally extending edges with rearwardly projecting side-flanges 3. The said side-flanges are provided at or near one end of the buckle-body, with a pair of perforations, as 4 and 5, or similar means, providing suitable journal or pintle-receiving bearings, for the purposes to be presently more fully set forth.

The reference-character 6 indicates a transversely extending member or bar of a loop-element, from which extends outwardly beyond the adjacent end of the 5 buckle-body a loop-portion 7 of any suitable configuration. The said member or bar 6 is provided at its opposite ends with journal-lugs or pintles 8, which are suitably disposed in the previously-mentioned 10 bearings 4 of the side-flanges 3, thereby pivotally connecting said loop-member between the said side-members, and spaced rearwardly from the back or inner face of the face-plate 2. Extending upwardly from 15 said transversely extending member or bar 6, and also spaced rearwardly from the back or inner face of the face-plate 2 is a cam-member, or gripping or clamping element, as 9, said member or element being 20 provided with a laterally and outwardly projecting convolution or convolutions 10, substantially as shown, and for the purposes to be presently more fully specified.

The reference-character 11 indicates another transversely extending member or bar, also provided at its opposite ends with journal-lugs or pintles 12, which are suitably disposed in the previously-mentioned 25 bearings 5 of the side-flanges 3, for pivotally disposing between said side flanges, a suitably convexed belt-body-gripping or clamping plate, as 13, which extends in a forward direction from said member or bar 11 directly above and over the above-mentioned 30 cam-member, or gripping or clamping element 9. As will be evident from an inspection of Figure 4 of the drawings, the said plate 13 is also provided with a laterally and downwardly projecting convolution or convolutions, as 14, and with a laterally and upwardly projecting convolution or convolutions, as 15.

The reference-character 16 indicates a belt-body of any suitable thickness, and in 40 attaching this belt-body to the buckle, one end 17 is looped and fastened about the free end of said loop-portion 7, so as to have a fixed relation thereto. In applying the belt and buckle to the waist of the 45 wearer, the belt-body 16 is carried around the waist, and the free end 18 of the belt-body is inserted between the back or inner face-plate 2 and the outer corrugated or ribbed face of the belt-gripping or clamping 50 plate 13. As the belt-body is drawn up tightly around the waist of the wearer, in the direction of the arrow α , see Figure 4, the pull or tension upon the loop-member 7, swings the latter in a direction toward 55 the back or inner face of the face-plate 2, thereby moving the convolution or rib 10 of the cam-member or gripping or clamping element 9 forcibly into contact and over the inwardly or downwardly projecting

convolution or rib 14 of the plate 13, the 65 convolution or rib 10 in passing over said convolution or rib 14 passing back of the same with an audible and positive snap, so as to positively lock the parts in place, and firmly forcing the upwardly projecting convolution or rib 15 into biting or gripping relation with the belt-body, whereby the latter is firmly gripped between the buckle-body and the clamping or gripping plate 13, and the free end of the belt is held unyieldingly 70 against withdrawal from such engaged relation to the buckle.

Owing to the peculiar shape, position and arrangement of the serrated or convoluted clamping or gripping plate 13, relative to the 75 serrated or convoluted cam-member or bar of the loop-member 7, the co-relation of said parts are rendered more or less yieldable, so that the buckle-body may be positively secured to belt-bodies of greater or less 80 thickness than the usual thickness without any loss of clamping effect, the snap-lock effect of the parts positively securing the belt and buckle in their adjusted relation about the waist of the wearer against any 85 accidental displacement, as will be clearly understood. To release the parts from the gripped or clamped relation with the belt-body, all that is necessary is to swing the 90 loop-member 7 in the direction of the arrow y , indicated in Figure 3 of the drawings.

Referring now to the belt-buckle shown in Figures 6 and 7 of the drawings, the general construction of the buckle is the 100 same as that described herein-above in connection with the belt-buckle represented in said Figures 1 to 5 inclusive, except that both the transversely extending member or bar 6 of the loop-element of the buckle and 105 the transversely extending member or bar 11 of the belt-body gripping or clamping plate 13 are provided with co-operating releasing means for more quickly releasing the plate 110 from its holding or binding engagement with the belt-body, when the loop-portion 7 is swung in the direction of the above-mentioned arrow y .

One form of such releasing means, as here 115 shown, consists of a suitable lug or extension, as 19, with which the said member or bar 6 is provided, the said member or bar 11 being also provided with a lug or extension, as 20, the free end of said lug or extension 120 projecting beneath the flat surface of the lug or extension 19, and being adapted to be brought into slidable engagement therewith when the loop-portion 7 is moved in the direction of the arrow y , and 125 whereby the rotary movement of the said loop-element will cause a corresponding movement of the belt-body gripping or clamping plate 13 in a direction away from

the belt-body, as will be clearly understood from an inspection of said Figures 6 and 7 of the drawings.

Of course I am aware, that some changes 5 may be made in the general arrangements and combinations of the several devices and parts, as well as in the details of the construction of the said parts, as set forth in the foregoing specification, and as defined in the 10 clauses of the claims which are appended thereto. Hence, I do not limit my present invention to the exact arrangements and combinations of the various devices and parts as described in the said specification, 15 nor do I confine myself to the exact details of the construction of the said parts, as illustrated in the accompanying drawings.

I claim:—

1. In combination, with a buckle-body, a 20 pivoted loop-element adjacent to one end of said buckle-body, said loop-element comprising a transversely extending bar and a clamping or gripping member formed integrally therewith, said member extending forwardly 25 and curving upwardly and then extending rearwardly to a point above said laterally extending bar, and a laterally extending convolution carried by the rearwardly extending part of said gripping or clamping member. 30 2. In combination, with a buckle-body, a pivoted loop-element adjacent to one end of said buckle-body, said loop-element comprising a transversely extending clamping or gripping member formed integrally there- 35 with and curved upwardly and rearwardly, a laterally extending convolution projecting from said upwardly and rearwardly curved part of said gripping or clamping member, and a pivoted belt-body clamping or grip- 40 ping element, said latter element being also provided with a laterally extending convolution with which the convolution of said loop- 45 element is adapted to be brought into locked engagement.

3. A belt-buckle comprising a face-plate and longitudinally and rearwardly extending side-members, combined with a loop-element, and a belt-body gripping or clamping element, both said loop-element and said 50 gripping or clamping element being independently pivotally disposed between said side-members adjacent to one end of said face-plate, said loop-member comprising a transversely extending bar and a clamping 55 or gripping member formed integrally therewith, said member extending forwardly and being curved upwardly and then extending rearwardly to a point above said bar, and means connected with said latter member 60 adapted to be brought into locked engagement with said pivoted belt-body gripping or clamping element.

4. A belt-buckle comprising a face-plate and longitudinally and rearwardly extend-

ing side-members, combined with a loop-element, and a belt-body gripping or clamping element, both said loop-element and said gripping or clamping element being independently pivotally disposed between said side-members adjacent to one end of said face-plate, said loop-member comprising a transversely and upwardly and rearwardly extending member, a convolution extending from said latter member, and a convolution extending from said belt-body gripping or clamping element with which the convolution of said transversely and upwardly and rearwardly extending member is adapted to be brought into locked engagement to force said belt-body gripping or clamping element 80 into gripping or clamping engagement with a belt-body.

5. A belt-buckle comprising a face-plate and longitudinally and rearwardly extending side-members, a loop-element pivotally 85 connected with said side-members, said element comprising a transversely and upwardly and rearwardly extending member, a convolution projecting from said member, a belt-body gripping or clamping element 90 also pivotally connected with said side-members, said gripping or clamping element comprising a convexed gripping or clamping plate, convolutions extending, respectively 95 downwardly and upwardly from said plate, the convolution of said transversely and rearwardly and upwardly extending member of the loop-element being adapted to be forcibly brought into locked engagement with the downwardly extending convolution of the 100 gripping or clamping plate of said gripping or clamping element for forcing the upwardly extending convolution of said plate into gripping or clamping relation with a belt-body.

6. In combination, with a buckle-body, a pivoted loop-element comprising a laterally extending bar, an off-set member extending from said bar, and a clamping member extending from said off-set member, and a biting convolution carried by said off-set member.

7. In combination, with a buckle-body, a pivoted loop-element comprising a laterally extending bar, an off-set member extending from said bar, said off-set member comprising a portion located substantially in the plane of said loop-element and of its bar, a clamping member extending from said off-set member, but being located in a plane above the plane of said loop-element and its bar, and a biting convolution carried by said clamping member.

8. A belt-buckle comprising a body-member, a clamp device pivoted to said body-member, said clamp-device comprising a base-portion, a loop-member projecting outwardly from the outer edge of said base-

portion, a jaw-body integrally formed with said base-portion to spring from the outer edge of the latter intermediate the side-arms of said loop-member, said jaw-body being curved upwardly and rearwardly, and a biting convolution carried by the rearwardly extending portion of the jaw-body.

In testimony, that I claim the invention set forth above I have hereunto set my hand this 5th day of May, 1921.

SAMUEL M. RIKER.
